UNITED STATES PATENT OFFICE.

HARRY G. LARCOM, OF NEW YORK, N. Y.

BOILER-FEEDER.

SPECIFICATION forming part of Letters Patent No. 698,296, dated April 22, 1902.

Application filed May 15, 1901. Serial No. 60,330. (No model.)

To all whom it may concern:

Be it known that I, HARRY G. LARCOM, a citizen of the United States, and a resident of the city of New York, borough of Manhattan, 5 in the county and State of New York, have invented a new and Improved Boiler-Feeder, of which the following is a full, clear, and exact description.

This invention relates to an apparatus for feeding boilers in which the steam-pressure of the boiler is transmitted to the feeder and the water allowed to fall by gravity into the boiler.

This specification is a specific description 15 of one form of my invention, while the claims are definitions of the actual scope thereof.

Reference is to be had to the accompanying drawings, forming a part of this specification, in which similar characters of reference indicate corresponding parts in all the views.

Figure 1 is an elevational view of the invention. Fig. 2 is a section on the line 2 2 of Fig. 1. Fig. 3 is a section on the line 3 3 of Fig. 2. Fig. 4 is an elevational view of the outer casing. Fig. 5 is an elevational view of the revolving barrel, and Fig. 6 is a section of the same.

The outer casing *a* of the device has four branches, (designated *a'*, *a''*, *a'''*, and *a''''*, respectively,) these branches leading into the casing each by means of a number of openings *a⁵*. According to the construction here shown each series of openings *a⁵* is composed of four openings. With the branch *a'* communicates a pipe *b*, leading steam from the boiler. With the branch *a''* communicates a pipe *c*, leading feed-water from a pump of any sort, which pump is conventionally illustrated at *d* in Fig. 1. From the branch *a'''* 30 leads a pipe *e*, carrying the feed-water to the boiler, and from the branch *a''''* leads a pipe *f*, carrying the water-overflow back to the source of feed-water supply. The casing *a* is tapered, as indicated best in Fig. 2, and within 35 this casing revolvably fits a correspondingly-tapered barrel *g*. This barrel has its large end fitted with a screw-cap *g'*, which closes the end of the barrel and which also carries a stud *g²*, passing through a stuffing-box in 40 the end of the casing *a* and carrying fixedly a ratchet-wheel *h*. With this ratchet-wheel *h* works a pawl *h'*, carried on an elbow-lever

h², the fulcrum of which coincides with the axis of the stud *g²*. The elbow-lever *h²* is rocked through the action of a lever *h³*, fulcrumed on an arm *a⁶*, carried by the casing *a*. The lever *h³* is suitably connected with the pump *d* or with any other source of motion, so as to impart a rocking action to the lever *h²* and drive the pawl *h'* against the ratchet-wheel *h*, 55 thus imparting a step-by-step movement to the barrel *g*. This barrel, as best shown in Figs. 5 and 6, is provided with a number of pairs of transversely-alined openings *g³*. These pairs of openings *g³* correspond in number 60 with the number of openings in each series *a⁵* of the casing *a*, and therefore in the present instance there are four pairs of openings *g³*. Each pair of openings *g³* is in transverse alignment with one opening of each series *a⁵* of 70 the casing *a*, as is best illustrated in Figs. 2 and 3. Within the barrel *g* and tapered to conform to the shape thereof is an interior barrel *i*, which is provided with three partitions *i'*, dividing the barrel into four compartments. The larger end of the barrel *i* is closed by the cap *g'*, and the smaller end of the barrel *i* is closed by a cap *i'*, which has a square stem *i³* projected into a chamber *a⁷*, 75 carried on the casing *a* and pressed by a spring *i⁴*, by means of which spring the barrel *i* is held snugly engaged with the barrel *g*. The barrel *i* is provided with four series of openings *i⁵*. The members of these series of openings are each arranged in longitudinal alignment, and the series of openings are disposed 80 equidistant around the circumference of the barrel.

The parts being constructed and arranged as shown and the pump being in operation, 90 the barrel *g* will be driven with an intermittent turning movement within the casing *a*. By adjusting the connection between the parts *h²* and *h³* the movement of the barrel *g* may be regulated. Referring now to Fig. 3, 95 it will be seen that the barrel *g* is in such position as will place the pipes *b* and *e* in communication with each other through one of the four compartments of the interior barrel *i*. Assuming that water is within this compartment of the barrel *i*, the steam-pressure of the boiler will be communicated to this compartment of the barrel *i*, and the water will flow by gravity into the boiler through 100

the pipe *e*. The barrel *g* now continues its movement, and the openings *g*³, which are shown in Fig. 3, will then be placed in communication with the openings *a*⁵, leading to the pipes *c* and *f*. The water from the pump will now flow into the before-referred-to compartment of the barrel *i* and fill this compartment. The barrel *g* then continues its movement and returns to the position shown in Fig. 3, whereupon the above-described operation is repeated. This accounts for the operation which goes on within one of the four compartments of the interior barrel. It should be understood, of course, that all of the other compartments are operating in the same way in succession. This successive, and therefore practically continuous, action is brought about by the spiral disposition of the pairs of openings *g*³ in the barrel *g*. These four pairs of openings are quartered around the barrel, and as the barrel moves in its action it brings each pair of openings rapidly into successive action. The desired height of the water in the boiler may be regulated by the elevation of the feeder, and when the water in the bottom reaches an elevation equal to the elevation in the casing *a* the feeding action will cease, since the feeder operates by force of gravity, and the water will not be forced into the boiler at an elevation higher than the elevation of the top side of the barrel *i*. Should the boiler be full, the water will simply be forced by the pump from the pipe *c* into the pipe *f* and back to the source.

Having thus described my invention, I claim as new and desire to secure by Letters Patent—

1. A boiler-feeder, comprising a casing having orifices respectively in communication with the feed-water supply, the boiler-supply and the boiler-steam-pressure, an orificed barrel arranged to turn in the casing and to command the orifices thereof, and a stationary barrel arranged in the first-named barrel and orificed in conformity with the orifices in the casing.

2. A boiler-feeder, comprising a casing having orifices respectively in communication

with the feed-water supply, the boiler-supply, and the boiler-steam-pressure, an orificed barrel arranged to turn in the casing, and a second orificed barrel stationary within the first-named barrel and having its orifices in conformity with the orifices in the casing, said second barrel having partitions forming it into separate compartments, for the purpose specified.

3. A boiler-feeder, having a casing adapted to communicate with the feed-water supply, the boiler steam-pressure and the boiler-feed, a barrel arranged to turn in the casing and having orifices communicating alternately with the feed-water supply, the boiler-pressure and the boiler-feed, said barrel having the orifices therein arranged spirally around it for the purpose specified, and a second barrel held stationary within the first barrel and having openings commanded by the moving barrel, such openings of the stationary barrel being respectively related with the feed-water supply, the boiler-supply and the boiler steam-pressure.

4. A boiler-feeder having a casing, adapted to communicate with the feed-water supply, the boiler steam-pressure and the boiler-feed, a barrel arranged to turn in the casing, and having orifices communicating alternately with the feed-water supply, the boiler-pressure and the boiler-feed, said barrel having orifices therein arranged spirally around it for the purpose specified, and a second barrel held stationary within the first barrel, and having openings covered and uncovered by the first barrel, such openings of the second barrel being respectively related to the feed-water supply, the boiler-supply and the boiler steam-pressure, and transverse partitions fastened in the second barrel and between the openings thereof.

In testimony whereof I have signed my name to this specification in the presence of two subscribing witnesses.

HARRY G. LARCOM.
